COMPRESSOR UNLOADER

Andrew A. Kucher, Dayton, Ohio, assignor, by
mesne assignments, to General Motors Cor-
poration, a corporation of Delaware

Application June 4, 1932, Serial No. 615,348

4 Claims. (Cl. 230—29)

This invention relates to compressors or pumps for compressing or pumping refrigerants or fluids.

It is among the objects of this invention to provide a device to enable a compressor or pump to start under a reduced load and in which the mechanism for accomplishing this purpose is of a simple nature, has few parts, and is capable of accomplishing the unloading of the compressor effectively and immediately, and, if desired, even before the compressor has come to a full stop.

Further objects and advantages of the present invention will be apparent from the following description, reference being had to the accompanying drawings, wherein a preferred form of the present invention is clearly shown.

In the drawings:

Fig. 1 is a vertical cross-sectional view of a compressor or pump embodying features of my invention;

Fig. 2 is a top plan view, partly broken away, of a portion of the mechanism shown in Fig. 1, the parts being shown when the compressor has attained normal speed;

Fig. 3 is a view similar to Fig. 2, but in which the parts are shown when the compressor is idle;

Fig. 4 is an enlarged cross-sectional view taken along the line 4—4 of Fig. 1;

Fig. 5 is an exploded view, in perspective, of the drive shaft and the unloading means, parts being shown broken away;

Fig. 6 is an enlarged view of a portion of the mechanism under running conditions, shown in Fig. 2, but with parts broken away in a different manner to show the underlying mechanism;

Fig. 7 is a view similar to Fig. 6, but showing the positions which the parts occupy when the compressor is idle;

Fig. 8 is a vertical cross-sectional view of a portion of a compressor utilizing the slightly modified form of the unloading device;

Fig. 9 is a top plan view, with portions broken away of the mechanism shown in Fig. 8; and

Fig. 10 is a detail of a portion of the sealing ring used to seal hermetically the casing which encloses the compressor.

One embodiment of a compressor built in accordance with my invention, has a cylinder or wall, a piston or impeller, a drive shaft, and an eccentric drive between the shaft and piston or impeller for causing the piston or impeller and the cylinder or wall to produce a pumping action, and, with these parts, there is provided a means or device which is responsive to starting conditions, or to reduced speed conditions, in the compressor for varying the eccentricity of

the drive between the drive shaft and the piston or impeller, so that the starting load of the compressor is materially reduced during the starting period or whenever the compressor operates at a reduced speed. In this manner, it is possible to drive the compressor with a driving device which does not need to have an exceptionally high starting torque, such as a split phase motor with the assurance that the motor will be capable of driving the compressor without stalling.

In order that the invention may be clearly understood, I have shown it applied to a compressor of the rotary type, it being understood that the illustration of my invention in connection with a rotary compressor in no way limits the scope of its usefulness, since the invention is capable of application to many other types of compressors.

In the embodiment shown in Figs. 1 to 7 inclusive, the compressor includes a casing generally designated by 10, in which are placed a motor 11 and compressing mechanism driven by the motor, which includes a stationary, circular wall, or cylinder 12 with which a piston or impeller 13 cooperates. The piston or impeller 13 preferably includes a circular or cylindrical portion depending from a plate 14 which rides on top of the stationary plate 15 in which the wall or cylinder 12 is cut. The impeller 13 cooperates with the wall 12 to produce a pumping action, and, to this end, it is given a rotary or gyratory motion within the wall 12, so that it causes the pumping chamber 16 to rotate or follow a path from the edge 17 of the divider block 18, around the wall 12, finally terminating in the other edge 19 of the divider block 18. An intake opening 20 is provided adjacent the edge 17, so that refrigerant, or other fluid, may enter the space between the wall or cylinder 12 and the piston or impeller 13, this fluid being forced by the rotary or gyratory movement through the pumping chamber 16 against the edge 19 of the impeller block 18, from whence the refrigerant or fluid passes upwardly through an opening 21 in the plate 14 past the valve 22 and into the space 23 of the casing 10. A suitable discharge opening is provided in the casing 10 so that the compressed refrigerant or fluid may be discharged to the required place. In this particular embodiment, the compressed refrigerant passes through passages in the mechanism to the space 24 of the casing 10 and is then discharged through the opening 25 to the pipe 26 which leads to a condenser 27, from whence the condensed refrigerant is discharged into a receiver 28. The liquid

55

refrigerant is then expanded through a suitable expansion device 29 and enters the evaporator 30^a from whence the evaporated refrigerant is returned by the pipe 31^a past the check valve 32^a to the intake passage 20.

The compressor may be single acting or it may be double acting, and in this particular embodiment it has been shown as a double acting rotary compressor. To this end a second wall or cylinder 30 is provided inside of the impeller or piston 13. This wall also may be a stationary circular or cylindrical wall and the impeller may be provided with a circular rotary or gyratory wall 31 which cooperates with the wall 30 to form an interior pumping chamber 32 similar to the chamber 16, but removed therefrom by an arc of 180°. The chamber 32 is fed by the extension 33 of the intake-opening 20 which extension is cut through the impeller 13 and leads to a place adjacent to the edge 17 of the impeller 18. The plate 14 is provided with an opening 34, similar to the opening 21, leading to the top of the plate on which is placed a valve 35 past which the refrigerant compressed in chamber 32 is discharged into the space 23.

The particular compressing mechanism above described may be taken to be typical of any compressing mechanism to which my unloader may be connected. The unloader is such that it provides a maximum eccentric drive between the shaft and the impeller when the compressor has attained a predetermined or normal speed and which varies this eccentricity when the compressor stops or is not running at the normal speed or a speed slower than the predetermined speed. In this particular embodiment, a drive shaft 40 is provided which has an eccentric drive between said shaft and the piston or impeller 13, the main axis of the shaft 40 being indicated at 40x, Fig. 5. This eccentric drive may include eccentric extension 41 of reduced diameter which has an axis 42. A further reduced extension 43 is placed on the extension 41 for a purpose more fully to be described. An eccentric sleeve 44 fits rotatably over the extension 41 and this sleeve 44 has an external diameter eccentric with its internal diameter as clearly shown in Fig. 5 and the external diameter of sleeve 44 has its axis at 44x. The total maximum eccentricity produced by the eccentricity of extension 41 and the sleeve 44 is the distance between the axis 40x and 44x, and this is the eccentricity required to maintain the piston and the cylinder of the compressor in pumping cooperation. A suitable bearing is provided between the sleeve 44 and the impeller 13. Preferably this bearing is formed by the annular ball bearing race 46 which, being truly annular, does not change the eccentricity established by the extension 41 and the sleeve 44. When the extension 41 and sleeve 44 occupy the relative angular position indicated in Figs. 1, 2, 4, 5, and 6 they produce the maximum eccentricity required; but when the extension 41 is rotated relatively to sleeve 44 so that they occupy positions indicated in Figs. 3 and 7 their composite eccentricity is reduced, so that the pumping efficiency of the compressor during the starting period is reduced or destroyed entirely.

A mechanism responsive to starting conditions is provided for producing a relative rotational movement between the sleeve 44 and the extension 41 so as to vary the total or composite eccentricity produced by these members during the starting condition of the compressor. Preferably this mechanism is a centrifugally responsive

mechanism, although it is to be understood that any function of the starting condition of the compressor or its driving member may be utilized to produce this relative rotational movement. In this particular embodiment, a centrifugal device 5 actuates sleeve 44, so that the sleeve 44 has its maximum eccentricity in alignment with the maximum eccentricity of the extension 41 when the compressor is at normal speed. This is accomplished by means of one or more weights 47 10 which occupy an extended position at full speed and which are retracted by spring means 47x or the like when the compressor stops or runs at a sub-normal speed. A pair of weights 47 are provided with slots 48 which cooperate with pins 49 15 formed on the extension 50 of the sleeve 44. When the compressor is at full speed, the pins 49 are held at positions corresponding to the maximum eccentric position and when the weights 47 are retracted the pins are rotated relatively to 20 the extension 41 so that the maximum eccentricity is reduced. To this end the weights 47 are pivotally mounted on the plate 51 by means of pins 52. The pins 52 are held in holes 53 of the plate 51, and the plate 51 is fitted over the extension 43 and keyed therein by the key 54. The holes 53 are equally distant from the axis 40x of the main portion of the shaft 40, so that when the weights 47 are at their extended position, they are statically balanced, since they rotate 30 about the main axis 40x, and this static balance is maintained also during starting conditions since the weights tend to occupy symmetrical positions about the axis 40x throughout the starting period. In view of this, the unloader is balanced at all speeds.

The motor 11 may be connected to the shaft 40 in any suitable manner but preferably is connected by attaching the rotor 60 to the shaft 40, the rotor being driven by the stator 61 mounted 40 in the portion 62 of the casing 10. The compressed refrigerant in the space 23 passes through the ball race 46 and through the openings 63 into the space 24 and is discharged through opening 25 as heretofore described. Lubricant is placed in 45 the compressor and normally occupies the lower portion of the casing 10. It passes through the screen 64 and through the opening 65 into the sump 66. The thread 67 on the shaft 40 acts as a pump and lifts the lubricant to the radial opening 68 from whence the lubricant is forced through the central bore 69 and is discharged through the opening 70 on top of the compressor so as to maintain a body of lubricant in the space 23 and thus insure a proper sealing of the compressor. A radial opening 71 permits a portion of the lubricant to pass to the spiral groove 72 in order to lubricate the bearing 73.

The casing 10 is hermetically sealed by any suitable means, which may include a copper wire 60 74, originally cylindrical in cross-section, which is formed into a ring by telescoping the ends of the wire as at 74a shown in Fig. 10, this joint being properly soldered before the ring is placed in the casing 10. The top 75 of the casing 10 is bolted 65 down onto the copper ring by means of bolts 76 as will be apparent from the drawings. A similar joint, if necessary, is provided in the lower portion of the casing.

In the modification shown in Figs. 8 and 9, a 70 single weight is used. To this end the shaft 40' is provided with an eccentric extension 41' on which is mounted the eccentric sleeve 44'. The sleeve 44' is provided with a plate 80 having a vertical extension 81 through which the arm 82 75

of the weight 83 slidably passes. An anchor 84 provided with a hook 85 pivotally holds the inner end of the arm 82 and is firmly held by means of the bolt 86 onto the shaft 40'. A spring 87 is connected at one end to the plate 88 which is keyed with the hook 85 to the shaft 40' and has its other end connected to the extension 81. It will be noted that the weight 83 is forced by the spring 87 so as to reduce the eccentricity and that the weight 83 flies out and produces the normal or maximum eccentricity when the motor assumes its normal speed, substantially in the same manner in which correspondingly numbered parts operate in Figs. 1 to 7.

15. While the form of embodiment of the invention as herein disclosed, constitutes a preferred form, it is to be understood that other forms might be adopted, all coming within the scope of the claims which follow.

20. What is claimed is as follows:

1. A compressor comprising a stationary horizontal cylinder plate having an annular groove therein provided with fluid inlet and outlet ports forming a pumping chamber, a piston plate resting on said cylinder plate for sliding engagement therewith and having a pumping ring extending into said groove, said ring being of less diameter than said groove and having a slot therein, a divider block passing through said slot and positioned between said inlet and outlet ports and having cylindrical ends which have bearing in arcuate recesses in the side walls of said groove in said cylinder plate and having straight sides cooperating with said slot in said ring, a shaft 25 having an eccentric portion on which portion said piston plate is rotatably mounted, the said eccentric portion being drivingly connected to said piston plate to cause gyration thereof within said pumping chamber, means for rotating said shaft, 30 means biasing said pumping ring into concentric relationship with said groove when the compressor is at rest or at low operating speeds, and centrifugal means for overcoming said biasing means and increasing the eccentricity of said eccentric portion when the speed of said compressor exceeds a predetermined limit whereby said ring will be brought into pumping engagement with said pumping chamber.

40. 2. In a rotary compressor, means forming an annular pumping chamber, inlet and outlet means for said chamber, a pumping ring of less diameter than said chamber located within said chamber, means between said inlet and outlet means cooperating with said pumping ring and the walls of said pumping chamber so as to completely close off the pumping chamber between

the inlet and the outlet means, a shaft having an eccentric portion on which portion said pumping ring is rotatably mounted, the said eccentric portion being drivingly connected to said pumping ring to cause gyration thereof within said pumping chamber, means for rotating said shaft, means biasing said pumping ring into substantially concentric relationship with said chamber when the compressor is at rest or at low operating speeds, and centrifugal means for overcoming 10 said biasing means and increasing the eccentricity of said eccentric portion when the speed of said compressor exceeds a predetermined limit whereby said ring will be brought into pumping engagement with said pumping chamber. 15

3. In a rotary compressor, means forming an annular pumping chamber, inlet and outlet means for said chamber, a pumping ring of less diameter than said chamber located within said chamber, means between said inlet and outlet means 20 cooperating with said pumping ring and the walls of said pumping chamber so as to completely close off the pumping chamber between the inlet and the outlet means, a shaft having an eccentric portion on which portion said pumping ring is rotatably mounted, the said eccentric portion being drivingly connected to said pumping ring to cause gyration thereof within said pumping chamber, means for rotating said shaft, 25 means carried by said shaft biasing said pumping ring into substantially concentric relationship with said chamber when the compressor is at rest or at low operating speeds, and centrifugal means carried by said shaft for overcoming said biasing means and increasing the eccentricity of 30 said eccentric portion when the speed of said compressor exceeds a predetermined limit whereby said ring will be brought into pumping engagement with said pumping chamber. 35

4. A rotary compressor comprising means forming a cylinder having a cylindrical wall, inlet and outlet ports for said cylinder, a divider block between said ports, a cylindrical piston of less diameter than said cylinder, means for positioning said piston in varying eccentric relation within said cylinder, means including a driving shaft on which said piston is mounted whereby the axis of said piston is caused to revolve about a center within the cylindrical wall of said cylinder, means for maintaining the piston in substantially concentric relation with said cylinder wall when the piston is stationary, and speed responsive means for moving said piston into varying eccentric relation with said cylindrical wall in accordance with the speed of said shaft. 45 50 55

ANDREW A. KUCHER.
